FASTENER FOR WALL PANELS

John G. Hamilton, McComb, Miss.

Application July 8, 1935, Serial No. 30,336

6 Claims. (Cl. 72—118)

This invention relates to the fabrication of the inner walls of buildings and like structures from panel units made of the usual substances such as pressed fiber, wood pulp, bagasse pulp, 5 plaster board, ply wood, etc., and of any size from small pieces simulating tile to large sheets of room height.

The general object of the invention is to provide fastening devices for securing such wall 10 units as above suggested and others, to the studding or underlying surface of the building structure and/or to secure such units together, the fasteners being concealed relative to the exposed side of the wall.

15 The invention is exemplified in several embodiments each of which fulfills, in addition to the general object, certain specific objects peculiar to each.

One of the specific objects of the invention 20 is to provide a fastener that shall penetrate through the mid thickness of adjacent units and be securable to the underlying studding by a nail or the like, proceeding diagonally through that part of one unit lying beneath the fastener 25 whereby said unit is pressed into intimate contact with the studding, and providing an inclined plane for drawing the adjacent unit into close contact with the studding.

Another object of the invention is the provision 30 of a fastener consisting of two parts, one of which is securable to the studding and the other penetrating the back portions of adjacent sheets and being movable relative to the secured portion so that the wall as a whole may move, 35 responsive to the aggregate expansion and contraction of the unit which compose it without cracks opening between any of said units. This arrangement makes it possible to use wall paper over wall surfaces on which its use has hitherto been impracticable on account of the shrinkage 40 of the units and opening of fissures between them, and also eliminates the use of metal tape, the countersinking of nails, putting the joints, and the use of furring strips over the joints.

45 Another object of the invention is the provision of pointed fasteners adapted to be employed in pairs, each having a portion adapted to underlie the meeting edges of adjacent sheets and having oppositely directed pointed portions penetrating thickness-wise of said adjacent edges, one member of said pair being secured directly to the underlying stud and the other member being held in place by the sheet which overlies it.

50 A still further object of the invention is the provision of a fastener of Z-shaped longitudi-

5 nal section adapted to have its underlying portion secured to a stud having a pointed portion adapted to penetrate a sheet at an intermediate depth along its tongue edge, the groove edge of the adjacent sheet being adapted to seat in the dihedral bend of said fastener for retaining the said grooved edge in place.

Other objects of the invention will appear as the following description of several illustrative embodiments thereof proceeds.

10 In the drawings which accompany and form a part of the following specification and throughout the several figures of which the same characters of reference have been employed to designate identical parts:

15 Figure 1 is a plan view showing wall units secured together and to studding by means constituting one form of my invention;

Figure 2 is a longitudinal section taken along the line 2—2 of Figure 1;

20 Figure 3 is a perspective view of a fastener, the piercing portions being barbed;

Figure 4 is a perspective view of a slightly modified form in which the ends are unbarbed;

25 Figure 5 is a vertical elevation showing the use of one element of the expansion fastener for fixedly anchoring the end sheet to a wall;

Figure 6 is a section taken on the line 6—6 of Figure 5;

30 Figure 7 is a perspective view of the expansion fastener;

Figure 8 is a vertical elevation showing another form of fastener;

35 Figure 9 is a longitudinal section taken along the line 9—9 of Figure 8;

Figure 10 is a perspective view of the fastener shown in Figure 8;

Figure 11 is a perspective view of a similar fastener provided with barbs;

40 Figure 12 is a vertical elevation of still another form of fastener;

Figure 13 is a longitudinal section taken along the line 13—13 of Figure 12; and

45 Figure 14 is a perspective view of the fastener shown in Figure 12.

Referring now in detail to the several figures of the drawings, and first adverting to that form of the invention shown in Figures 1 to 3, inclusive, the numerals 1 and 2 represent adjacent sheet wall units or panels spanning the spaces 50 between studding 3 and being secured to the studding. The sheets in this form of the invention have edges 4 lying in planes perpendicular to their front and back surfaces of said sheet, the sheets and studding being related as is com- 55

mon in building practice so that they meet in the middle of a piece of studding. The fastener comprises a metal sprig 5 bent so as to have a perpendicular web 6 and upper and lower pointed portions 7 and 8. The pointed portion 7 is flat while the pointed portion 8 has an intermediate bend 9 best shown in Figure 2 defining a plane 10 inclining downwardly toward the bottom of the web 6. The upper angle of fold, between the pointed portion 7 and the web 6 is provided with a hole 11 preferably on an inclined axis. The pointed portions 7 and 8 may be barbed as shown at 12 in Figure 3 or unbarbed as in that form of the invention shown in Figure 4.

15 The fastener of Figures 3 and 4 is employed as follows: The pointed portion 7 is stuck into the side edge of the panel 2 as shown in Figure 2 intermediate the front and back surfaces. The panel is laid against the stud and a nail is driven 20 diagonally through the hole 11 into the stud 3, thus securing the fastener in place. It will be observed that the nail penetrates that portion of the panel 2 which lies below the embedded portion of the fastener and thus draws the panel 25 into close contact with the stud 3. The presence of metal beneath the nail head prevents the nail tearing into the edge of the panel which is a particularly desirable feature where the panel is of loosely pressed fibrous material such as 30 35 characterizes some insulation board. Since the fastener lies intermediate the exposed and inner surfaces of the wall, the nail head is concealed. The adjacent panel is thrust sidewise upon the pointed portion 8 until it has penetrated the panel 1 to its full depth and the sides 4 of the adjacent panels come into close contact. The inclined plane 10 of the pointed portion 8 crowds the material of the panel down into the restricted place between the stud and said inclined plane 40 45 and thus holds the panel 1 into close contact with the stud 3. In Figure 2 both pointed portions of the fastener are provided with the barbs 12 which prevent the panels working away from one another. Separation of the panels is however positively prevented by means of the nail which secures the opposite edge of the panel 2 to the studding 3 which said opposite edge overlies.

50 The barbs 12 may be objectionable from the standpoint of discomfort in handling through injury to the workman's fingers. Therefore, the modification shown in Figure 4 has been developed which is similar to Figure 3 in all respects excepting that the barbs 12 have been 55 omitted. This form of the invention is used in exactly the same way as that form shown in the first three figures and the two panels will stay together by virtue of the nails which anchor their corresponding edges.

60 In Figures 5 to 7, inclusive, a form of invention is shown in which the fastener comprises a fixed base 13 adapted to be secured to the studding by nails driven through holes 14 and 15 in said base. The base is stamped out so as to form 65 a broad trough or channel 16 bridged in a transverse direction by a strip 17. A movable cleat 18 is slidably seated in the channel 16 and passes beneath the strip 17 which normally holds it inseparable with respect to the base 13. The 70 cleat 18 is free to slide longitudinally or sideways and in the form of the invention shown, it is lightly held in position for application by the formation of a bead 19 upstanding from the bottom of the channel 16 and received within a

groove 20 on the bottom of the cleat 18. The cleat has teeth 21 and 22 adapted to be driven in the back surface of a panel or wall unit. The teeth are preferably curved so that when driven into the wall unit a component of the driving force acts in a direction to deflect the teeth 21 and 22 which grip the material of the adjacent sheets as indicated in Figure 6 on the left hand side. The length of the teeth 21 and 22 is such that when they are in fully interlocked position 10 with respect to the adjacent building sheets they fall short of penetrating the exposed face of the building unit and therefore remain concealed. Between the teeth 21 and 22 is a small ribbed 15 prong 22' which not only penetrates the wall board, but reinforces the bases of the teeth 21 and 22 so that the bending of these teeth is concentrated near their free ends ensuring the penetration of the teeth to the proper depth in the wall panel.

20 It is obvious from Figure 6 that due to expansion and contraction of the wall, the sheets 1 and 2 can move as a unit either to the right or left or up or down without developing a crack between them.

25 Certain wall board compositions contract and expand under varying conditions of temperature and atmospheric hygroscopicity to such an extent that cracks develop between the sheets when the boards contract and bulge and warping develops when the boards expand, walls constructed from such units being unadapted for decorating with wall paper. So universally is this limitation recognized that the manufacturers of 30 certain composition wall boards advertise that their product is not adapted for wall paper, thus greatly restricting its field of usefulness. The fastener of the present invention can be employed to prevent the opening of cracks and fissures in 35 wall board of this description. In employing the 40 invention for this purpose, it is essential that a side wall of a room be firmly anchored to the studding adjacent one corner of the room. This is accomplished by disassembling several of the 45 expansion fasteners such as are shown in Figure 7 by slipping the cleat 18 from under the bridge strip 17. This is made possible through the fact that the bottom of the channel 16 is cut out on 50 opposite sides of the strip 17 forming a hole or opening 23 of considerable width, underlying said strip. When the cleat 18 has been pushed as far as possible either to the right or left, it may, thanks to the opening 23 be rotated about the bridge strip 17 as an axis and be readily removed. Several of these strips are nailed at vertical 55 intervals along a corner stud, one being shown in Figure 5. The first panel is then laid against the stud and the fasteners which have been affixed thereto and hammered on the front or exposed side above said fasteners so as to make the teeth 60 65 21 and 22 penetrate the back side of said sheet and interlock with the substance of the sheet. Now, it is clear that due to the fixation of the cleats 18, the panel cannot shift either to the right or left. Now, along the studding which 70 underlies the opposite edge of this first panel, a plurality of the complete expansion fasteners are secured in vertical relation and the studding of the first sheet secured to the cleats 18 of the complete expansion fasteners by hammering on the exposed surface of the panel above said fasteners in the manner described. The adjacent second sheet is then put in place with its edge abutting the edge of the first sheet as is clearly 75 shown on the left hand side of Figure 6. The

second sheet is then hammered to drive the teeth 21 and 22 through its back surface. The successive sheets are laid in similar manner.

The base 13 is provided with transversely extending faces 13' lying flush in the plane of the bridge piece 17, their particular value being to afford a slideway for the second panel permitting it to be brought into abutment with the adjacent edge of the first panel without colliding with the side of the bridge piece and thereby prevented from making a close joint.

It is clear now that when expansion takes place, the capacity of the units to shrink separately has been eliminated and the entire wall moves relative to the edge which is anchored to the studding by the separated cleats 18 shown on the right hand side of Figure 5. This movement makes a crack or fissure in the opposite corner of the wall having a width equal to the aggregate gap which would otherwise occur between the several sheets, but this may be effectively concealed by a vertical corner bead or molding secured to the side wall which is adjacent to and perpendicular to the edge of the wall in which the fissure and crack develops, or by allowing the free expanding and contracting end of the wall to slide behind the adjacent wall at the anchored end of the latter.

If the expansion fastener is constructed so as to permit the cleat 18 to slide upwardly or downwardly as well as to the right and left, universal expansion and contraction is provided for both in the lateral and vertical directions.

Figures 8, 9 and 10 illustrate a form of the invention adapted particularly for large sheets having meeting edges which lie in planes perpendicular to the front and back surfaces of the sheets. These fasteners are used in pairs. A single fastener is shown in Figure 10 and consists of a sheet metal member 24 having a bayonet-shaped longitudinal cross section formed by folding the metal so as to provide an intermediate web 25, a securing lug 26 and a pointed embedded portion 27. For the sake of facility in manufacturing, all of the lugs 26 are provided with a nail hole 28, but in only one of a pair of fasteners is a nail applied. The method of procedure is as follows: The pointed portion 27 of one fastener is thrust into one edge of a wall panel intermediate its front and back surfaces and to the full depth of the pointed portion until the web 25 rests against the edge of the panel. The depth at which the pointed portion 27 is thrust into the panel is determined so that the lug 26 will be flush with the bottom surface of the panel. The lug 26 is then nailed to the underlying studding as is clearly shown at 29 in Figure 9. The other fastener of a pair is then thrust into the confronting edge of an adjacent panel with the lug 26 flush with the bottom of the panel and the panel is then pushed up into close contact with the first panel which has already been fixed to the stud, the lug 26 of the second panel sliding under the first panel, and the second panel resting above the lug 26 which projects from the first panel and concealing the same. There may be, if desired, two or three pairs of fasteners for each edge, the number used being determined by the rigidity of the material of the wall panel, and the height of the wall.

In Figure 10 this form of the invention is shown without barbs. It may however be provided with barbs 12 as shown in Figure 11 and the barbs would have the same function as the barbs described in connection with Figure 3.

The group of Figures 12 to 14, inclusive, illustrates a form of the invention which is particularly desirable for wall panels which interfit by means of cooperating tongues and grooves such as are shown respectively at 30 and 31, in Figure 13, in which 30 is the tongue and 31 the groove. Tongue and groove units may be of any size, but are customarily of small area and simulative of tile. The fastener exemplifying this modification is shown in Figure 14 and comprises a sheet metal member 32 of longitudinal Z-shaped cross section being folded to form dihedral angles 33 and 34 connected by a common inclined web 35. The upper pointed portion 36 of said member is designed to be forced into the edge of the panel along the apex of the tongue, the underlying portion of the tongue being received in the dihedral angle 33. The base portion 38 is provided with a nail hole 37. The unit 39 thus impaled is nailed to an underlying stud through the nail hole 37 as shown in Figure 13. The adjacent panel has its grooved side brought into conjunction with the tongue on the panel already laid, and overlying the base portion 38 and with the lower edge of its groove received in the dihedral angle 34.

The above construction enables adjacent units to be laid close with the complete concealing of the fastener and the second unit laid will be maintained in close contact with the tongue of the first unit by the fastener 40 at the opposite side of said second unit and which is nailed to the stud which underlies the said opposite edge of said unit. In the laying of simulated tile, the fasteners 32 are arranged on one horizontal and one vertical edge of each unit.

While I have in the above description disclosed what I believe to be a preferred and practical embodiment of my invention, it will be understood by those skilled in the art that the details of construction as illustrated and described are merely by way of example and not to be construed as limiting the scope of the invention which is to be determined only by a fair interpretation of the appended claims.

What I claim is:

1. Concealed fastener for wall panels comprising a sheet metal member having an intermediate web and upper and lower portions debouching from said web in opposite directions, one of said portions being keen, for penetrating the substance of a panel from the edge surface thereof, the other of said portions being adapted to cooperate with an adjacent panel, said member having a nail hole for securing it by a nail to an underlying support.

2. Concealed fastener for wall panels comprising a sheet metal member having an intermediate web and upper and lower portions debouching from said web in opposite directions, one of said portions being keen, for penetrating the substance of a panel from the edge surface thereof, the other of said portions being adapted to cooperate with an adjacent panel, said member having a nail hole for securing it by a nail to an underlying support, the edges of said member being provided with slits, and edges of said slits being upset forming barbs.

3. Concealed fastener for wall panels comprising a sheet metal member having an intermediate web, and upper and lower portions debouching angularly from said web in opposite directions, said portions being keen, for penetrating the substance of adjacent panels from the edge surfaces thereof, said member having a nail hole penetrating the apex of the angle between said

web and upper portion, for securing said member to an underlying support by a nail driven obliquely through said hole, and the margin of the panel beneath the upper portion of said fastener.

5. Concealed fastener as claimed in claim 3, edges of said member being barbed.

5. Concealed fastener for wall panels having interfitting tongue and groove edges comprising a sheet metal member having an intermediate 10 web and upper and lower portions debouching from said web in opposite directions, one of said portions being keen for penetrating the substance of one panel from the edge surface thereof, the other of said portions being parallel to the first 15 mentioned portion and being adapted to cooperate with an adjacent panel, said web being inclined so as to form acute dihedral angles with said portions each of which angles is adapted

to receive a complementary part of the interfitting edges of said panels, said member having a nail hole for securing it by a nail to an underlying support.

6. Concealed fastener for wall panels comprising a sheet metal member having an intermediate web and upper and lower portions debouching angularly from said web in opposite directions, said portions being keen for penetrating the substance of adjacent panels from the edge surfaces thereof, said member having a nail hole by which it is adapted to be secured to an underlying support, one of said angularly debouching portions being formed with an intermediate part inclining downwardly from its free end toward 10 said web whereby a panel driven on to said free end is forced against the underlying support. 15

JOHN G. HAMILTON.
